United States Patent Office.

OLIVER CROOK, OF DAYTON, OHIO.

Letters Patent No. 67,509. dated August 6, 1867.

IMPROVEMENT IN BRIDLE-BITS.

The Schedule referred to in these Letters Patent and making part of the same.

TO ALL WHOM IT MAY CONCERN:

Be it known that I, OLIVER CROOK, of Dayton, in the county of Montgomery, in the State of Ohio, have invented a new and improved Bridle-Bit; and I do hereby declare that the following is a full and exact description thereof, reference being had to the accompanying drawing, and to the letters of reference marked thereon.

The nature of my invention consists in constructing a bridle-bit with orifices within the front part of the rings, through which straps pass connecting the lines to the headstall.

To enable others skilled in the art to make and use my invention, I will proceed to describe its construction and operation.

The figure represents a perspective view of the bridle-bit and the strap used within its orifices.

A represents a bridle-bit having a stiff bit-mouth, with rings B B, which have orifices C C, through which the strap D is used. This strap is buckled to the headstall, and to the opposite end is attached the ring E. This ring serves the double purpose, that of sustaining the bit within the horse's mouth, and as a connection for the driving-lines. This bit is made by casting it with a semicircular bit-mouth; it is then made malleable, and then the bit-mouth is straightened, suitable cores being used to produce the orifices. When the driver pulls upon the lines, the lines being continuous with the headstall, the bit is drawn up into the mouth, thereby serving as an efficient check to an unruly horse. In other respects it is used in the usual manner.

What I claim as my invention, and desire to secure by Letters Patent, is—

The bridle-bit A, having a stiff bit-mouth, with rings B B rigidly attached at either end, and the anterior portion of these rings having orifices through the centre for a strap connecting the driving-reins to the headstall, substantially as and for the purpose described.

OLIVER CROOK.
